MACHINE FOR MAKING COMPOSITION PLUGS.

1,348,214.

Specification of Letters Patent.

Patented Aug. 3, 1920.

Application filed July 5, 1919. Serial No. 308,758.

To all whom it may concern:

Be it known that I, IRA E. FARR, a citizen of the United States, residing at Watertown, in the county of Jefferson and State of New York, have invented certain new and useful Improvements in Machines for Making Composition Plugs, of which the following is a specification.

This invention relates to improvements in machines for making tapering plugs for paper rolls, and other molded articles.

The invention relates particularly to improvements in the devices shown and described in my United States Patent No. 1,248,097, dated November 27, 1917.

The object of the invention is to provide novel, simple and inexpensive mechanism for molding under pressure composition plugs or bushings, to take the place of the common wooden plugs heretofore employed for centering and supporting rolls of wrapping and other paper. A further object is to provide a machine for making plugs in which a plurality of molds are continuously rotated for successively bringing said molds into the charging, compression and discharging positions, and wherein novel and simple timing parts coöperate for rendering the machine automatic. And a particular object is to provide a powerful automatic rotary machine of the class, which is capable of compressing a pasty composition into light, compact plugs, which will retain their shape and size, and which can be made in large numbers at a relatively low cost.

I attain these objects by the means set forth in the detailed description which follows, and as illustrated by the accompanying drawings, in which—

Figure 1 is a front end elevation of the complete machine. Fig. 2 is a front side elevation of the same. Fig. 3 is a vertical transverse section, taken on line 3—3 of Fig. 4; showing one of the compression cams in relation to other parts of the device. Fig. 4 is a vertical longitudinal section, taken on line 4—4 of Fig. 1. Figs. 5 and 6 are respectively an end and an edge view enlarged of one of the plugs molded by the machine. Fig. 7 is a view of one of the rotary cams which lock the mold covers.

In the drawings, 2 represents generally a frame preferably made out of castiron, having a suitable base 3, and front and rear end portions 4 and 5. The power for operating the working parts of the machine may be supplied from any source, and is applied to a main shaft 6, which is journaled in pillow-blocks 4' and 5', and is held in place by caps 4" and 5". 7 is a relatively large and heavy cylinder or drum, which is mounted upon and driven by the shaft 6 by means of a key 6'. The cylinder 7 is preferably cast-iron, and is provided at its opposite ends with heavy annular flanges 7'. Inside of 65 the flanges 7' the drum is provided with longitudinal radial slots or windows 8, which are spaced equidistantly around the drum. On the peripheral face of the drum 7 and in line with the slots 8, are disposed a 70 number of blocks 9, which extend longitudinally substantially the length of the drum, and these blocks are secured to the drum by bolts 9' (see Fig. 4). Each block 9 is provided with a pair of relatively large 75 circular sockets 9", whose axes register with corresponding circular sockets 10 formed in the periphery of the drum, the latter registering and communicating with the slots 8. In the sockets 9" are disposed the tapering 80 molds, in which the plugs 11' are made under pressure. The molds 11 are preferably made by expanding one end of brass or other suitable metal tubes, the bodies 11" of which project through the blocks 9 and partially through the flange rim of the drum, preferably concentric to the sockets 9" and 10. The outer ends of the sockets 9" are 85 preferably larger than the flaring molds 11, so as to provide a suitable space to be filled 90 with molten lead 9", which rigidly holds the molds in place. The sockets 10 are of relatively large diameter so as to accommodate various sizes of the molds 11 without necessitating the alteration of the drum 7. The 95 plugs 11' are preferably made out of a composition composed principally of old newspaper stock, lime and cement, which is prepared in the form of a thick watery paste, and this paste is forced into the molds 100 11 by a suitable charging mechanism (not shown) while the drum is rotating, and is

afterward compressed and molded into solid and substantially dry masses by means of plungers 12, which reciprocate in the tubes 11^a. The plungers 12 are mounted on the outer threaded ends of hollow rods 12', while the inner ends of said rods are made rigid in cross-heads 13, which play radially in the slots 8. Each cross-head 13 supports and operates two of the plungers 12, as best seen in Fig. 4. As the plugs 11' must be perforated centrally, to receive the shafts which support the rolls of paper, this is accomplished by cores 14, which are disposed centrally in the molds 11. The upper ends of the cores are preferably flush with the outer ends of the molds 11, and the cores then extend inwardly through the plungers 12, the rods 12', and through the cross heads 13, and their inner ends are rigidly anchored in the web of the drum 7, as at 14'. The opposite ends of each cross-head extend beyond the corresponding faces of the drum, and are provided with rollers 13', which engage the peripheral surfaces of similar cams 15—15', which are disposed close to the opposite ends of the drum 7, the cams being made rigid to the upright frame portions 4 and 5 by bolts 15^a. The rollers 13' are in constant engagement with the cams which are stationary, while the drum is in constant rotation. In order to suitably confine the pulp in the molds 11 during the compression of the plugs, the outer face of each block 9 is provided with two plates 16—16', each of which has a group or perforations 16^a, which are normally disposed over the mouths of the molds 11, and through which the water contained in the composition escapes during the molding operations. The plates 16 are secured at their opposite ends by parallel bars 17, which are disposed alongside of the blocks 9. All of the bars 17 project a considerable distance beyond the opposite ends of the blocks 9 (see Figs. 2 and 4), and are held in place by a plurality of dogs 18, whose stems 18' are loosely inserted through holes in the flanges 7' of the drum. The heads of the dogs 18 are slotted to receive the bars 17, and said bars are movable longitudinally when the tension on the dogs is relaxed, for effecting the shifting of the plates 16 for uncovering the molds, as shown in Fig. 2, for permitting the ejection of the plugs and the refilling of the molds with the wet composition. The inner ends of the stems 18' pass through tie-plates 18^a, which are held in place by nuts 18^b. The portion of the stems 18' which extends between the drum and the heads of the dogs are fitted with compression springs 18^c, which tend to relax the grip of the dogs on the bars 17, and permit said bars to be reciprocated for uncovering as well as covering the molds.

65 As the operation of the machine is in-

tended to be as nearly automatic as possible, it is necessary to provide certain timing means, for opening the molds for the discharge of the plugs, for filling the molds with fresh charges of the pulp, for closing the molds again, and for holding the covers 16 in place during the compression operations. The various timing attachments will now be described.

19 represents a series of pinions, which are journaled on shafts 19', the latter being rigidly set in the opposite ends of the drum 7, in line with the slots 8, as shown in Figs. 1 and 4. The pinions 19 are rigid with cams 20, which rotate in circular sockets 20' cut in the flanges 7', at the opposite ends of the drum (see Figs. 3 and 4). These cams are so arranged that their throw-points successively engage the tie-plates 18^a which are attached to the stems 18' of the dogs, and when so engaged the said cams draw the dogs inwardly against the tension of the springs 18^c, for holding the plates 16—16' in both the closed and the open positions, shown in Figs. 1, 2 and 4. The cams 20 are operated intermittently by pinions 19, by means of mutilated racks 21—21' and 21^a—21^b, as best seen in Figs. 1 and 4. The bars 17 which support the plates 16 are moved endwise for uncovering the molds, by a wedge-like cam or shift 22, which is mounted on a bracket 22', the latter being supported by the base 3 (see Figs. 1 and 4). The bars 17 are moved in the opposite direction for re-covering the molds 11 by a similar wedge-cam 22^a mounted on a bracket 22', which is supported by the cap 5^a (see Figs. 1, 2, 4). The mechanism for filling the molds with the pulp is preferably a separate attachment and its not shown, as any suitable filling means may be employed.

The operation of my rotary plug molding machine is as follows: Assuming that the molds 11 shown in section at the top of Fig. 1, have been filled, and closed by the plates 16, and are ready for the compression operation, the roller 13' shown at the end of the plain portion N of the cam 15, at the start of the machine, immediately begins to climb the first rather abrupt rise of the cam indicated at α . The object of this steep rise of the cam is to effect a quick initial compression of the pulp which contains considerable water and therefore offers less resistance to the pressure at the start of the operation, than it does later on after the composition becomes relatively dry and compact. As the drum 7 is rotated in the direction of the arrows in Fig. 1, the rollers 13' after ascending the first rise α , continue to climb the cam for a distance of substantially 180° , or until the pinion 19 encounters the first series of rack-teeth 21. The engagement of the pinion with the said teeth rotates the pinion a fraction of a turn, which moves the cor-

responding cam 20 sufficiently to release the dogs 18 and allow the springs 18^c to move said dogs outwardly, thus relaxing their grip on the bars 17. As the drum 7 continues to rotate, the ends of the bar 17 engage the first of the wedge-cams, 22, which moves said bars in the direction for simultaneously uncovering the molds 11 of that particular block 9. At the time the pinions 19 engage the teeth 21, the plungers 12 have about completed the compressing of the plug, and are ready to begin the work of ejecting the plugs. This, however, cannot be done until the plates 16 are moved away from the mouths of the molds 11. In order to prevent injury to the machine, during the interval between the completion of the plugs and the opening of the molds, the cams 15—15' continue for a space indicated by the characters α — α , for a short distance without any increase of rise. As soon as the pinions become free from the teeth 21, the wedge 22 begins to uncover the molds, as described, and by the time they are uncovered, the pinions 19 engage the second set of teeth 21', which operate the cams 20 for locking the plates 16 in the open position. While this latter work is being done, the rollers 13' start to climb the last rise of the cams 15—15', which again is rather abrupt, and causes the plungers 12 to force the completed plugs outwardly free from the molds. The final ejection of the plugs occurs when the rollers 13' reach the highest points 15^c of the cams, after which the said rollers, the plungers 12 and the cross-heads 13 gravitate back to the starting points, shown at the left side of Fig. 1, from whence the cams 15—15', for a distance of substantially 90° describe a true and neutral arc, indicated by the letter N. After each set of molds 11 pass the points 15^c of the cams 15—15', the filling of the molds is effected in the interval or space indicated by the bracket A (Fig. 1). As the refilled molds approach the wedge 22^a, the pinions 19 engage the rack-teeth 21^a, which effects the unlocking of the plates 16 while still in the open position. Then the bars 17 are forced toward the right by the wedge 22^a (see Figs. 2 and 4), which moves the plates 16 in the direction for closing the molds. By the time the molds are closed, as described, the pinions 19 engage the rack-teeth 21^b, which again locks the plates in the closed position shown in Figs. 1 and 4, ready for a subsequent pressing operation. Each pair of molds 11 in regular order are filled, and their charges compressed, as described, during each revolution of drum 7. But seven of the mold blocks 9, each having two molds 11 are shown in the drawings. In practice twenty or more pairs of molds are provided, and the capacity of each machine, when operated at the normal speed of one

revolution of the drum per minute, is approximately twenty-five thousand plugs per day.

Having thus described my invention, what I claim as new and desire to secure by Letters Patent, is—

1. A machine for making composition plugs, including a frame, a rotatable drum journaled in said frame, said drum having a plurality of radial slots, a plurality of molds arranged in pairs mounted on the periphery of said drum in line with said slots, plungers reciprocatable in said molds, a pair of similar cams carried by said frame, and means connecting said plungers with said cams for effecting the compression strokes of the cams. 75

2. A machine for making composition plugs, including a frame, a drum rotatable in said frame, a pair of cams carried by said frame and disposed at the opposite ends of said drum, a plurality of molds arranged in pairs mounted on the periphery of said drum, plungers operable radially for compressing composition in said molds, and means for operatively connecting said plungers with said cams for effecting the compression strokes of said plungers and for ejecting the plugs from the molds. 90

3. A machine for making composition plugs, including a frame, a drum rotatable in said frame, a pair of cams carried by said frame and disposed at the opposite ends of said drum, a plurality of molds arranged in pairs mounted on the periphery of said drum, plungers operable radially for compression of composition in said molds, means for operatively connecting said plungers with said cams for effecting the compression strokes of said plungers and 100 for ejecting the plugs from the molds, and a timing mechanism comprising a plurality of pinions and a plurality of mutilated racks for effecting the opening and closing of said molds while the drum is in motion. 110

4. A machine for making composition plugs, including a frame, a rotatable drum journaled in said frame, a plurality of molds arranged in pairs mounted on the periphery of said drum, plungers reciprocatable in said molds, a pair of stationary similar cams between which said drum rotates, means for connecting said plungers and said cams for effecting the compression strokes of said plungers, and wedge-cams 120 for effecting the opening and closing of said molds while the drum is in motion. 115

5. A machine for making composition plugs, including a frame, a drum rotatable in said frame, said drum having a plurality of radial slots spaced equidistantly, a plurality of molds arranged in pairs mounted on said drum in line axially with said slots, plungers reciprocatable in said molds, cross-heads movable radially in said slots and op- 125 130

eratively connected to said plungers, said cross-heads provided with end-rollers, and a pair of cams adapted to be engaged by said rollers for effecting the compression strokes of said plungers.

6. A machine for making composition plugs, including a frame, a drum rotatable in said frame, a pair of cams carried by said frame and disposed at the opposite ends of said drum, molds arranged in pairs mounted on the periphery of said drum, plungers operable radially for compressing composition in said molds, means for operatively connecting said plungers with said cams for effecting the compression strokes of said plungers, perforated covers for said molds, means for moving said covers toward and away from said molds while the drum is in motion, and means for locking the covers in the open as well as in the closed position.

7. In a machine for making composition plugs, the combination with the frame, of a pair of similar cams supported by said frame, a rotatable drum journaled in said frame between said cams, a plurality of molds mounted on the periphery of said drum adapted to be filled with wet composition, plungers for compressing said composition, means engaging said cams and connecting with said plungers for effecting the compression strokes of said plungers, and means for opening and closing said molds once during each revolution of said drum.

8. In a machine for molding composition plugs, the combination with the frame, of a pair of cams supported by said frame, a drum journaled in said frame between said cams, a plurality of molds arranged in pairs mounted on said drum adapted to be filled with wet composition, covers for each of said molds, means for moving said covers toward and away from the molds while the drum is in motion, means for locking said covers in the open as well as in the closed position, plungers reciprocatable in said

molds, means engaging said cams and connecting with said plungers, adapted to effect the compression of the composition in said molds and the ejection of the product of said molds, and a core disposed centrally in each mold and passing through each plunger.

9. The combination with a frame and a drum rotatable in said frame, a plurality of molds arranged in pairs mounted on the periphery of said drum, plungers for compressing composition in said molds, cams carried by said frame for effecting the compression strokes of said plungers, covers for said molds, parallel bars supporting said covers, dogs for locking said bars in different positions, rotary cams for holding said dogs in the locked positions, pinions for operating said cams, mutilated racks for operating said pinions, and wedge-cams for moving said covers toward and away from said molds.

10. The combination with a frame and a pair of rigid cams supported by said frame, of a drum rotatable between said cams, said drum having radial slots and corresponding sockets, cross-heads movable in said slots in one direction by engagement with said cams, a plurality of blocks mounted on the periphery of said drum having sockets aligning with the sockets of said drum, molds disposed in said sockets, cores disposed in said molds, plungers reciprocatable in said molds and bored out to receive and slide on said cores, covers for said molds, dogs for locking said covers in the closed and open positions, bars for tying each pair of dogs together, cams engaging said tie-bars, pinions for operating said cams, mutilated racks for operating said pinions at the end of each compression stroke of the plungers, and similar racks for operating said pinions after each refilling of said molds, and means for moving said covers toward and away from said molds.

In testimony whereof I affix my signature.
IRA E. FARR.
